SPRING DEVICE

Filed Jan. 22, 1931

UNITED STATES PATENT OFFICE

CHARLES I. NYGARD, OF ELMHURST, NEW YORK

SPRING DEVICE

Application filed January 22, 1931. Serial No. 510,419.

This invention relates to springs of various kinds and classes; and the object of the invention is to provide a spring wherein the cross section of the wire or strand from which the same is formed is substantially of I-beam cross sectional form and consists of comparatively thick side portions and a thinner intermediate or central portion; a further object being to provide a spring, the separate 10 coils of which include opposite side faces which are arc-shaped and concaved in cross sectional form; a still further object being to provide a spring of the class specified which by virtue of its construction, will produce 15 greater strength as well as greater resiliency, notwithstanding the fact that less material by weight is employed in the structure of the spring; a further object being to provide a spring which by virtue of its 20 cross sectional form will permit the use of a greater number of coils within the smallest possible space especially in the construction of conical springs; a further object consists in the novel method of forming the wire used 25 in coiling the spring as herein described and claimed; and with these and other objects in view, the invention consists in a spring of the class and for the purpose specified which is simple in construction, efficient in use, and 30 which is constructed as hereinafter described and claimed.

The invention is fully disclosed in the following specification, of which the accompanying drawings form a part, in which 35 the separate parts of my improvement are designated by suitable reference characters in each of the views, and in which:

Fig. 1 is a side and sectional view of a 40 combined compression, expansion and torsional spring.

Fig. 2 is a view similar to Fig. 1 showing a compression spring.

Fig. 3 is a similar view of an extension spring.

Fig. 4 is an end view of a torsional spring.

Fig. 5 is a view similar to Fig. 4 of a conical spring.

Fig. 6 is an enlarged, cross sectional view of one form of strand from which my improved springs are formed; and,

Fig. 7 is a view similar to Fig. 6 showing a modification.

In carrying my invention into effect, I fashion elongated strip material used in the construction of springs of various kinds and classes, examples of which are shown in Figs. 55 1 to 5 inclusive, by drawing, rolling or otherwise forming the strand into a cross sectional contour similar to that shown in Figs. 6 and 7 of the drawings. In both of these figures, a strand of substantially I-beam cross sectional form is disclosed.

In Fig. 6 of the drawings, the strand 10 is 65 fashioned to form arc-shaped or slightly rounded side edges 11 and 12 which extend into concaved arc-shaped side faces 13 and 14 of the strip through what might be termed rounded beads or ribs 15 and 16 arranged longitudinally of the strand, thus producing the substantially I-beam cross sectional form. In 70 other words, the transverse dimensions of the strand at the sections 15—16 is materially greater than the transverse dimensions between the central portions of the arc-shaped 75 surfaces 13—14.

The structure shown in Fig. 7 is substantially identical to that shown in Fig. 5 in general contour, except that the side edges 11a and 12a are flattened and the surfaces 15a and 16a are also flattened, whereas the 80 surfaces 13a and 14a are arc-shaped and concaved similar to the surfaces 13 and 14. In some cases, the cross sectional form of spring shown in Fig. 7 would be more desirable than that shown in Fig. 6. It will be understood 85 that either cross sectional form may be used in the construction of the several springs shown in Figs. 1 to 5 inclusive. For illustrative purposes, the cross section shown in Fig. 6 has been incorporated in the formation of the springs referred to.

In Fig. 1, I have shown at 17 the combined expansion, compression and torsional spring including several coils or windings 17a of the 95 cross sectional form shown in Fig. 6 as is indicated in the lower left hand corner of Fig. 1. The ends of the spring 17 terminate in oppositely disposed coupling loops 17b and 17c. This type of spring has many 100

uses, such as example, in conjunction with engine starting devices and like apparatus.

In Fig. 2 of the drawings, I have shown at 18, a plain compression spring, the separate windings 18a of which are of the cross sectional form shown in Fig. 6.

In Fig. 3 of the drawings, I have shown a spring 19 of the extension type, the coils 19a of which are of similar cross sectional form, the ends of the coils terminating in coupling loops 19b and 19c which may be fashioned to suit any particular type of apparatus or device to which said ends are coupled.

In Fig. 4 of the drawings, I have shown at 20 a torsional spring, the coils 20a of which are formed in accordance with my improved cross sectional form. The opposite ends of the spring terminate in angularly disposed 20 arc-shaped arms 20b and 20c for attachment to suitable supports.

In Fig. 5 of the drawings, I have shown at 21 a conical spring, the coils 21a of which are of the cross sectional form shown in Fig. 6. It is preferred that the enlarged portion 15—16 of one coil or winding be disposed centrally of an adjacent coil so that the enlarged portion may be nested within the arc-shaped recess 13—14 of an adjacent coil, thus 30 permitting a more compact collapsing of the spring as will be apparent. With this type of spring construction, a larger number of coils may be used within a given length to produce greater power and resiliency.

In addition to the feature of my improved spring as referred to in the description of Fig. 5, the particular cross sectional form of the separate coils or windings produces the greatest possible strength, and at the same 40 time, effects a saving in the amount of material employed and further increases the resilient or tensional properties of the spring.

While, in the several views, I have shown springs, the coils of which are wound with 45 the wide surfaces of the coils in opposed relation, it will be apparent that springs of the types disclosed may be wound with the narrow edges in adjacent relation. This type of spring construction is especially desirable 50 where the clearance space externally of the spring is limited, and by virtue of the structure of the spring employed, the greatest possible strength will be provided.

It will be understood that the different 55 forms of springs herein disclosed are merely a few examples of the many types of springs that can be constructed in accordance with my invention. It will also be understood that my invention is not limited 60 in any way to the particular character of the material employed in the strand from which the coils of the spring are formed. Various changes in and modifications of the construction herein shown and described 65 may be made within the scope of the ap-

pended claims without departing from the spirit of my invention or sacrificing its advantages.

Having fully described my invention, what I claim as new and desire to secure by Letters Patent, is:

1. A torsional coil spring of the class described fashioned from a strip of wire of the same dimensions throughout its length, the wire being of greater width than thickness, the wide side faces of said strip being concave to form curved, arc-shaped recesses extending centrally and longitudinally of the strip throughout the entire spring formed thereby, and the separate coils of the spring being wound in close proximity to each other to form spaces between the coils of less dimensions than the thickness of said coils. 75

2. A coil spring for engine starters, said spring being fashioned from a strip of wire of the same dimensions throughout its length, the wire being of greater width than thickness, the wide side faces of said strip being concave to form curved, arc-shaped recesses extending centrally and longitudinally of the strip throughout the entire spring formed thereby, the separate coils of the spring being wound in close proximity to each other to form spaces between the coils of less dimensions than the thickness of said coils, and the end coils of said spring terminating in curved loops disposed on one side edge of the spring with said loops arranged in the plane of the coils of the spring. 90

In testimony that I claim the foregoing 100 as my invention I have signed my name this 21st day of January 1931.

CHARLES I. NYGARD.
